UNITED STATES PATENT OFFICE.

CAID H. PECK, OF ATHENS, PENNSYLVANIA, ASSIGNOR TO INGERSOLL-RAND COMPANY, OF NEW YORK, N. Y., A CORPORATION OF NEW JERSEY.

FLUID-OPERATED DRILL AND HANDLE THEREFOR.

1,105,998.

Specification of Letters Patent.

Patented Aug. 4, 1914.

Application filed June 14, 1912. Serial No. 703,765.

To all whom it may concern:

Be it known that I, CAID H. PECK, a citizen of the United States, residing at Athens, in the county of Bradford and State of Pennsylvania, have invented certain new and useful Improvements in Fluid-Operated Drills and Handles Therefor, of which the following is a specification.

This invention relates to fluid operated drills of the type used for drilling holes in close proximity to walls or in other positions where the space is limited in one or more directions and more particularly to a drill of this type which is provided with 10 an additional handle which can be removably secured to it enabling it to be used for general drilling purposes.

Drills of this type such as shown in my copending application Serial #703763, filed 20 June 14th, 1912 are necessarily long and narrow on account of the restricted places in which they must be used and are provided with but a single handle which projects from the end of the tool opposite to the drill 25 spindle. It is therefore almost impossible to use such a drill in any situation where the feed screw can not be brought into operation. Furthermore as the drill spindle must be at the extreme limit of the drill 30 casing in one direction at least, and in practice is usually as close as possible to the outside of the casing in three directions to enable the drill to be used in restricted passages closed at one end, it is not feasible to 35 secure a handle to the drill itself by bolts or screws with sufficient strength unless the size of the casing is materially increased because of interference with the action of the drill.

40 The object of this invention is to produce a drill of this type with an easily removable handle.

A further object of the invention is to produce a drill and a handle of such construction that the handle may be firmly secured to the drill without interfering with its operation when it is desired to use it for ordinary drilling work and which can be easily removed when it is desired to use the 45 drill for special work in drilling in corners and restricted spaces for which its construction is particularly adapted.

With this object in view I have devised

a drill and a handle therefor, a practical embodiment of which is shown in the accompanying drawings in which—

Figure 1 is a side elevation of the drill with handle attached Fig. 2 is a plan view of the spindle end of the drill with the handle in position and Fig. 3 is a side elevation of the 60 handle un-attached to the drill.

The drill as shown comprises a casing 1 at one end of which is secured a handle 2 and at the other end of which is a drill spindle bearing sleeve 3. The internal construction of the drill forms no part of the present invention and is fully described in my copending application, mentioned above. The spindle bearing sleeve extends upwardly and downwardly from the drill casing forming 70 opposite cylindrical projections 4 and 5. The handle consists of a saddle piece 6 fitting over the end of the drill. This saddle piece is provided at its lower end with a collar 7 which fits over the cylindrical projection 5 and at its upper end with a similar collar composed partly of the saddle piece itself and partly of a semicylindrical retaining piece 8 which is adapted to be secured to the saddle piece 6 by bolts 9 which 80 pass through projecting lugs 10 on the retaining piece and the saddle piece. Secured to the saddle piece 6 is a handle grip 11 which may be of any desired shape.

In operation: when it is desired to use the 85 drill for ordinary purposes the collar 7 is slid over the lower projection 5 and the retaining piece 8 bolted to the upper part of the saddle piece 6 around the upper projection 4 thus fastening the handle firmly and 90 securely to the drill thereby enabling a single drill to be used for all purposes, which has heretofore not been possible on account of the necessary construction of the 95 drills used for work in restricted places.

It is to be understood that the present showing and description discloses only one specified modification of my invention and other forms and modifications are included in the spirit and scope of the invention as 100 expressed in the claims.

What I claim is:

1. The combination with a drilling machine comprising an elongated casing having a spindle bearing at one end, a handle 105 secured to the other end, and handle holding

projections on the casing coaxial with the spindle, of a second handle removably secured on said handle holding projections.

2. The combination with a drilling machine comprising an elongated casing with a spindle bearing at one end and a handle secured to the other end, said spindle bearing having ends projecting from said casing, of a second handle having fastening means removably secured on said projecting spindle ends.

3. The combination with a drilling machine comprising an elongated casing adapted for close corner work, a spindle bearing at one end of the casing having ends projecting from said casing, and a fixed handle on the other end, of a handle com-

prising a grip, a saddle piece for said grip, a collar on one end of the saddle piece fitting around one end of said spindle bearing, and a retaining piece partly surrounding the other end of said spindle bearing and removably secured to said saddle piece.

4. As an article of manufacture, a handle for attachment to a close corner drill comprising a saddle piece, a collar attached to one end of said saddle piece, a retaining piece removably secured to the other end of said saddle piece forming a second collar, and a handle grip on said saddle piece.

CAID H. PECK.
